(57) **CLAIM**

The ornamental design for a crossbow cocking device, as shown.

DESCRIPTION

FIG. 1 is a top perspective view of a crossbow cocking device, showing our new design;

FIG. 2 is an exploded perspective view thereof;

FIG. 3 is a front elevation view thereof;

FIG. 4 is a top plan view thereof;

FIG. 5 is a bottom plan view thereof;

FIG. 6 is a rear elevation view thereof;

FIG. 7 is a left side elevation view thereof; and,

FIG. 8 is a right side elevation view thereof.

The dash-dot broken lines in FIG. 2 drawing depict projection lines only and form no part of the claimed design.
